UNITED STATES PATENT OFFICE.

ALEXANDER M. LIBERTY, DECEASED, LATE OF FAUST, NEW YORK, BY LOUIS LA PORTE, ADMINISTRATOR, OF FAUST, NEW YORK.

VALVE GRINDER.

Application filed June 9, 1926. Serial No. 114,825.

This invention is a valve grinder for grinding, refacing and reseating the valves of internal combustion engines.

One object of the invention is to provide a relatively simple, practical and efficient tool for the purpose mentioned, the same being adapted for refacing in one operation and simultaneously, the contacting faces of both the valve and the valve seat without removing the valve from its mounting.

Another object is to furnish a handy means for applying the grinding compound.

In the drawing

Figure 1 is a vertical section through the improved tool as positioned for use upon a valve mounted in a cylinder block;

Figure 2 is a detail view of the tool as opened for positioning upon the work;

Figure 3 is a top end view of the tool;

Figure 4 is a bottom end view of the tool;

Figure 5 is a top plan view of the device taken in a plane cutting the rod 10 at right angles and slightly above the ring 9, the said rod 10 being shown in section.

The invention comprises a bell-like grinding thimble 1, made up of two longitudinally defined half sections 2 and 3 which are hinged together by a lower hinge 4 and so adapted to open apart. A turn handle 5 is rigidly attached near the upper end of the section 2 and extended horizontally and provided with a hand knob 6. The other section 3 is then hinged by an upper elongated hinge 7 to the handle 5 whereby the two bell sections are fully supported in hinged relation. The sections 2 and 3 being locked in closed relation, a press rod hole 8 is bored through the upper closed ends of the said sections, and a bearing ring 9 is rigidly mounted within the resulting semi-circular cut-out at the upper end of the section 2. A press rod 10 is passed through the ring 9 and is nicely turned to slidingly and rotatively engage the same. The lower end of this rod is rounded as shown at 11 to provide a frictionless rotative bearing upon the work and the upper end is provided with a hand knob 12.

An additional support is provided for the rod 10, in the way of a supporting lug 13 laterally extended from the inner wall of the section 2, and having a bearing hole 14 formed

through the outer end thereof in axial alignment with the said hole 8. The rod 10 is passed also through the hole 14 and is thus fully supported. A stop ring 15 is adjustably locked upon the rod 10 inside the thimble 1, by means of a set screw 16. A coil spring 17 is mounted over the rod 10 within the thimble 1 and is braced between the lug 13 and the ring 15, the normal action of the spring 17 being to force the rod 10 upwardly and away from the work. The sections 2 and 3 of the thimble 1 are provided at their lower edges with semi-circular bits 18. These bits are of slight thickness and have parallel upper and lower faces 19 and 20; they may be formed integral with the sections 2 and 3 and they are inclined obliquely downwardly and inwardly as shown, the angular inclination of the bits corresponding to the angular inclination of the mating faces of the valve 21 and valve seat 22. Grinding compound cups 23 and 24 are mounted upon the outer lower edges of the sections 2 and 3 and have branching ducts 25 and 26 extended through the bits 18 and opening out through the upper and lower faces thereof. These cups are provided with the usual threaded force plugs 23' and 24' for forcing the contents of the cups out through the ducts 25 and 26.

In use and operation the thimble sections 2 and 3 are opened apart and the bits 18 are passed under the valve 21 and positioned between the faces of the valve and valve seat 22; the sections 2 and 3 are then closed together and the valve 21 is caused to bear upon the upper faces of the bits 18 while the lower faces of these bits in turn bear upon the valve seat 22 so that the said bits are adapted to be operatively held to the work through the centering effect of pressure imposed upon the said valve, oblique bits and valve seat. The grinding process is performed by bearing downward upon the rod 10 and oscillating the handle 5, while simultaneously forcing coarse or fine grinding compounds out of the cups 23 or 24, as desired.

While there has been herein described a certain specific manner and method of constructing and assembling the elements of the invention, it is understood that they may vary from the same in minor details, not departing

from the spirit of the invention, so as best to construct a practical device for the purpose intended, as defined in the appended claim.

What is claimed is:

5. In a valve grinding tool embodying hingedly connected frame members, bits on said frame members adapted for insertion between the valve and valve seat; a spring set press rod journaled in one of said frame members

adapted to bear directly upon the center of the valve for supplying a steady working pressure, and a laterally extended operating handle on one of said frame members for imparting rotative movement to the bits.
